UNITED STATES PATENT OFFICE.

FRANK LINDEEN, OF CLINTON, ILLINOIS, ASSIGNOR OF ONE-FOURTH TO JASPER ARMSTRONG, OF CLINTON, ILLINOIS.

SAFETY DEVICE FOR POCKETS.

1,319,016.

Specification of Letters Patent.

Patented Oct. 14, 1919.

Application filed December 28, 1916. Serial No. 139,232.

To all whom it may concern:

Be it known that I, FRANK LINDEEN, a citizen of the United States, residing in Clinton, county of DeWitt, State of Illinois, 5 have invented certain new and useful Improvements in Safety Devices for Pockets, of which the following is a specification.

My invention relates to a safety device for pockets.

10 Various improvements in the modern art of clothes making having been devised from time to time, the idea being to perfect the system of manufacture, to lower the cost of making and at the same time to give tone 15 and elegance to the garment, to arrange convenient pockets and to generally render the same more attractive and salable.

15 The object of the present invention is to provide a safety device for pockets, which 20 will be so arranged that articles placed in a pocket cannot be dumped out or removed without inserting the hand.

25 To accomplish this I fit an additional pocket within the usual and outer pocket which is shorter than the outer pocket and is open at the bottom, *i. e.* it is provided with an opening which is normally closed by a folding and lapping flap that can be easily pushed downward and outward as the hand 30 enters to place articles within or remove them from the pocket.

35 I carry out the above and other objects as hereinafter set forth in the following description and as particularly pointed out in the appended claim, reference being had to the accompanying drawing in which an embodiment of my invention is shown.

In the drawings.

40 Figure 1 represents a fragment of a garment, preferably a part of a pair of trousers, with one side of a pocket opened and folded back to expose the inner safety pocket, the outline of two small supplementary pockets suitable for holding a knife, key and like 45 articles being indicated by stitching.

Fig. 2, is a detached side elevation of the safety pocket proper.

Fig. 3, is an enlarged fragmentary section taken on line 2-2 Fig. 2, and showing the 50 bottom lapping flap in closed position in full lines and in open position in dotted lines.

Fig. 4, is a fragmentary edge view of the safety pocket.

Fig. 5, is a fragmentary enlarged side 55 view of the upper right hand portion to illus-

trate the small supplementary pockets for holding a knife, keys, etc., a portion being broken away to expose the knife and keys in position.

In referring to the embodiment of my invention shown in the accompanying drawings in detail, like numerals designate corresponding parts.

While my improvement is shown specifically in the accompanying drawings, applied to a side pocket of trousers, it is equally applicable to and can be fitted in pockets of other garments.

In Fig. 1, a portion of a pair of trousers is shown in which, 1, indicates the cloth of the garment, 2, a part of the lining and 3, the pocket which to better disclose my improvement is opened and folded back to expose the interior of the pocket.

My improved safety attachment is preferably made of strong and substantial cloth or similar material and is arranged within the ordinary pocket being fastened therein at the top and left side and the lower right hand corner, and one part of the right hand side edge of the safety attachment being suitably secured to one side of the open mouth of the pocket, 3, and the other and opposite part to the opposite side of the pocket mouth.

As shown in Fig. 2, the safety attachment is made approximately similar in form to the pocket in which it is fitted and consists of two side portions or side walls 4, which are secured throughout their left hand side and top edges to the pocket and are also secured at the lower right hand corner to the pocket by suitable stitching, 5, 6 and 7.

The attachment is left open on the right hand side to provide a mouth or entrance 95 opening for the hand and the margins, 8, of said mouth or opening are secured by stitching, 9, to the opposite edges of the mouth or side opening leading into the pocket.

100 The bottom of the attachment is open but normally closed by a lapping flap, 10, which is integral with and an extension of the lower part of one of the side portions, 4. The flap, 10, is arranged substantially as shown in Figs. 1, 3 and 4, being lapped over the shorter portion, 4, and fastened at its opposite side edges by stitching as shown in Fig. 4.

When the hand is inserted the flap is 110

pushed downward from the position shown in full lines in Fig. 3, to the position shown in dotted lines in said figure.

This allows the hand to pass through and into the pocket. When the hand is withdrawn, the flap automatically resumes its normal lapping position and closes the bottom opening.

For conveniently carrying a knife, keys and other small articles, I prefer to arrange a plurality of individual small supplementary pockets in the upper right hand corner of the safety device.

These small pockets form individual and separate receptacles for small articles and hold them above the pocket proper and so that they may be instantly taken out when desired.

In Figs. 1, 2 and 5, I have shown two of these small pockets, the upper pocket, 11, being shaped to receive and hold a small pen knife while the lower pocket, 12, conveniently holds a set of keys, as illustrated in Fig. 5.

While I have described in the foregoing specification adaptations or embodiments of my invention it should be understood that the structural parts thereof may be varied,

changed, modified or altered or one or more may be omitted or dispensed with without departing from the spirit of my invention as fairly defined in the following claim, or as may be imparted thereto by invoking the doctrine of equivalents.

Having thus described my invention, what I claim to be new and patentable is:

A safety device for ordinary side pockets of trousers, said safety device being of a size to substantially fill the upper portion of such ordinary pocket and to extend slightly below the mouth or opening thereof, and composed of side walls stitched at the top inner side and lower front corner and having a vertical opening above said lower front corner, one of the side walls of the safety device being provided with a flap extending upwardly over the other side wall of the said safety device in overlapping relation with the same, and adapted to be opened to permit the hand to be passed through the safety device into the pocket.

FRANK LINDEEN.
